United States Patent Office.

CLINTON I. PAINE, OF YOUNG AMERICA, ILLINOIS.

Letters Patent No. 98,881, dated January 18, 1870.

STEAM-CULINARY APPARATUS.

The Schedule referred to in these Letters Patent and making part of the same.

To all whom it may concern:

Be it known that I, CLINTON I. PAINE, of Young America, in the county of Warren, and State of Illinois, have invented certain new and useful Improvements in Apparatus for Cooking by Steam; and I do hereby declare that the following is a full, clear, and exact description of the construction and operation of the same, reference being had to the accompanying drawings, making a part of this specification, in which—

Figure 1 is a perspective view of my invention.

Figure 2 is a vertical sectional view on the plane of the line $z z$, fig. 1.

Figure 3 is a side elevation.

Figure 4 is a cross-section of the vertical tubular heater or boiler.

Similar letters of reference indicate corresponding parts in all of the figures.

The nature of this invention relates to an apparatus for cooking by steam, portable and convenient for private families; and

The invention consists in a suitable frame, supporting a tubular boiler in a vertical position, on top of which is a cap-boiler, extending out over the vertical boiler, and having pipes extending from it, and connecting with the tubular boiler, near its lower end, the heated water ascending from the tubular boiler, directly into the cap-boiler, and the cold water descending in said pipes. A slide is connected with the frame, on which a lamp or other heater may be placed, and slid directly under the boiler.

The invention also consists in pipes, leading from the top of the cap-boiler, and connecting, the one with any suitable cooking-box, and the other with a hinged plate, for receiving coffee-boiler, fruit-cans, &c.

To enable others to understand the construction and operation of my invention, I will proceed to describe it, with reference to the drawings.

A is a vertical boiler, with tubes, P, extending through it.

A' is a pipe, connecting the boiler A with a cap-boiler, B.

C is a small cap, screwed on a spout, where the water may be replenished in the boiler A.

J J are pipes, leading from the lower part of the cap-boiler B to the lower part of the vertical boiler A.

E is a slide, running on the pieces D' of the supporting-frame, and carrying the oil-box F and lamps H, the lamps H H coming immediately under the pipes or tubes P P.

Heat being applied by means of the lamps H H, or their equivalents, the heated water and steam will as-

cend through the central and heated part of the boiler, to the upper surface of the cap-boiler B, whilst the water in the exposed pipes J J, being colder and heavier, will descend, and an action of this kind be established, sending the steam and hotter water to the surface, while the colder water is carried down the pipes J J, and brought in contact with the lower end of the pipes P P, to be heated and propelled upward along the heated tubes P P.

I represents a cooking-box, which may be arranged with suitable compartments for holding flesh, vegetables, &c., and is supported on the frame D.

N is a pipe, leading from the upper part of cap-boiler B, to this box I, and passes the steam from the boiler to the box, for the purpose of cooking articles contained therein.

L is a metal plate, hinged at L' to the frame D and boiler A, in a manner to admit swinging around.

N' is a pipe, conducting steam from the upper part of the boiler B to any vessel placed on the plate L, the pipe N' passing, as shown at fig. 2, to near the bottom of the coffee-pot M, or other vessel, in which condition water may be boiled in a few minutes, the plate L, being swung around while the vessel M is placed in position, and then brought back and under the vessel L, to hold it in place.

The construction of my boilers is such, in connection with the arrangement of pipes J J, as to furnish a great amount of steam with a comparatively small amount of heat, and the arrangement of the pipes N N', and box I, and plate L, is such as to furnish convenient, simple, and cheap means of using said steam for cooking-purposes.

What I claim as my invention, and desire to secure by Letters Patent, is—

1. The arrangement of the boiler A, tubes P P, pipes J J, cap-boiler B, and lamps H H, substantially as described, and for the purpose set forth.

2. The combination of the pipes N N', box I, and vessel M, with the cap-boiler B, tubular boiler A, and pipes J J, substantially as described and for the purpose set forth.

3. The plate L, combined with frame D, boiler A, and pipe N, substantially as described and for the purpose set forth.

Signed at Galesburg, Illinois, this 26th day of July, 1869.

CLINTON I. PAINE.
